CLAIM

The ornamental design for a vehicle wheel, as shown and described.

DESCRIPTION

FIG. 1 is a front view of a vehicle wheel.

FIG. 2 is a perspective view of the vehicle wheel; and, FIG. 3 is a left side view of the vehicle wheel.

The broken line showing of the rear of the rim, the valve stem hole, the bolt holes and the center hole in the central hub area is included for the purpose of illustrating environment and forms no part of the claimed design.
